LOCOMOTIVE SMOKE CONSUMER

Fred G. Stephens, Granite City, Ill.

Application July 1, 1937, Serial No. 151,398

5 Claims. (Cl. 299—141)

This invention relates to smoke consumers capable of general application in furnaces, locomotives, and the like.

An object of the invention is to provide a device adapted to be mounted in the combustion chamber of a locomotive or furnace for ejecting jets of steam in various directions into and through the smoke, etc., in the combustion chamber to cause more complete combustion of the lighter particles and substances that would otherwise pass to the outside.

Another object of the invention is to provide a device of the character mentioned including a member having therein a chamber for receiving steam, and outwardly diverging outlet openings from the chamber through which the steam may be discharged in various directions in the combustion chamber of a locomotive or furnace.

Another object of the invention is to provide a member of the character mentioned with a cover composed of refractory tile or carborundum, or other refractory substance, having holes therein registering with the outlet openings from the chamber in said member, and an interlocking device between said cover and said member holding the cover in position thereon.

Other objects of the invention will be apparent from the following description, reference being made to the annexed drawing, in which—

Fig. 1 is a vertical longitudinal sectional view of a portion of the locomotive comprising a fire-box and adjacent equipment, and having the present invention mounted therein.

Fig. 2 is an approximately vertical cross-sectional view on the line 2—2 of Fig. 1.

Fig. 3 is an enlarged sectional view approximately on the line 3—3 of Fig. 1.

Fig. 4 is a view illustrating a member forming the receiving chamber for the steam, the refractory cover being shown in section.

Fig. 5 is an inner side elevation of the upper portion of the device, the lower portion being in section.

For convenience of illustration, I have shown the present invention mounted in the fire-box of a locomotive, but the utility of the invention is not restricted to use in locomotives.

The member 1 is composed of metal including walls forming a steam receiving chamber 2. The wall 3 of the member 1 is curved, and a series of holes 4 open in outwardly diverging directions from said chamber 2. A compartment 5 is formed in the outer end of the member 1. The upper wall of the member 1 is formed with a transverse rib 6.

The refractory cover for the member 1, which

may be made of tile or carborundum, or any other suitable refractory material, comprises a body 7 having therein a compartment or space 8 in the upper wall of which a transverse groove 9 is formed. The vertical width of the compartment or space 8 is at least equal to the vertical width of the member 1 including the rib 6, so that said member may easily be inserted in said compartment or space 8 and the rib 6 engaged in the groove 9, leaving the lower end of the member 1 separated from the lower wall of the compartment 8 by an intervening space at least equal to the height of the rib 6.

The cover 7 is formed with a series of outwardly diverging and outwardly flaring passages 10 the inner ends of which register with the respective outlet openings 4. These devices are mounted in the fire-box or combustion chamber of the locomotive or furnace at the sides thereof, so that the jets of steam discharged through the openings 10 of one device will intersect the jets of steam discharged from the openings 10 in the cooperating and oppositely located device.

Pipes 11 extending through the side walls of the fire-box or combustion chamber have their inner ends screwed into openings in the end walls of the respective members 1, so as to discharge steam into the receiving chambers 2 and out through the passages 4 and 10. These tubes open into a source of steam supply and, as shown, they open into a pipe 12 which opens into the vapor fountain 13 on the top of the locomotive. The pipe 12 may be equipped with a valve 14 which may be opened and closed as desired.

When the invention is used in a locomotive, the devices are mounted upon the arch 15 in position so that jets of steam will be discharged transversely and in diverging directions toward the rear of the fire-box and obliquely upward. Thus, certain of the jets of steam discharged from the device at one side of the fire-box will intersect jets of steam discharged from the opposite side of the device, producing a cyclonic effect, with the result that nearly all of the lighter elements are burned instead of being discharged to the outside.

The construction and arrangement of the invention may be varied within the scope of equivalent limits without departure from the nature and principle thereof.

I claim:

1. A smoke consumer device comprising a member composed of vertical and horizontal metallic walls forming a receiving chamber, one of said vertical walls having an inlet opening and another

- of said vertical walls being curved about a vertical axis and having outwardly diverging outlet openings therethrough, a refractory cover, having an opening at one side for insertion and withdrawal of said member, supported by and closely enclosing said member and having therein outwardly diverging passages communicating with said openings respectively for discharging steam in several directions, and a projection on said member interlocking with said cover and preventing displacement of said cover.
2. A smoke consumer device comprising a member composed of top and bottom horizontal metallic walls, a number of vertical walls integrally connected with said horizontal walls one of which has an inlet opening, and a vertical wall curving about a vertical axis integrally connected with said first named vertical walls and with said horizontal walls and cooperating therewith to form a receiving chamber and having outwardly diverging outlet openings therethrough, a refractory body having a compartment provided with an opening at one side for insertion and withdrawal of said member and closely engaging all of the walls of said member other than the bottom wall thereof and the wall through which said pipe opens and having outwardly diverging passages registering with said outwardly diverging openings respectively, and means preventing displacement of said body from said member.
3. A smoke consumer device comprising a member composed of top and bottom walls, a side wall and an end wall integrally connected with said top and bottom walls and with each other, said end wall having an inlet opening, a curved vertical wall integrally connected with said top and bottom walls and with said side and end walls and cooperating therewith to form a receiving chamber and having outwardly diverging outlet openings therethrough, and a refractory body having a compartment provided with an opening at one end for insertion and withdrawal of said member and having walls fitting closely against said side wall and said top wall and said curved wall, respectively, of said member and having outwardly diverging passages registering with said outwardly diverging openings respectively.
4. A smoke consumer device comprising a member composed of top and bottom walls, a side wall and an end wall integrally connected with said top and bottom walls and with each other, one of said last named walls having an inlet opening and a curved vertical wall integrally connected with said top and bottom walls and with said side and end walls and cooperating therewith to form a receiving chamber and having outwardly diverging outlet openings therethrough, a refractory body having a compartment provided with an opening at one end for insertion and withdrawal of said member and having walls fitting closely against said side wall and said top wall and said curved wall, respectively, of said member and having outwardly diverging passages registering with said outwardly diverging openings respectively, one of the walls of said compartment having a recess therein, and a projection rigid with said member engaging in said recess and holding said body from displacement with respect to said member.
5. A smoke consumer device comprising a member composed of top and bottom walls, an end wall integrally connecting said top and bottom walls and having an inlet opening, two side walls integrally connecting said top and bottom walls and being integrally connected with each other and with said end wall, one of said side walls curving from integral connection with the other to integral connection with said end wall, all of said walls cooperating to form a receiving chamber, said curved wall having outwardly diverging outlet openings therethrough, a refractory body having a compartment provided with an opening at one end for insertion and withdrawal of said member, and means in connection with said member engaging within said refractory body and positively holding the same from displacement and holding said curved wall closely against the complementary wall of said chamber, said body having outwardly diverging passages registering with said outwardly diverging openings respectively.
